UNITED STATES PATENT OFFICE.

CHARLES H. ALLEN, OF PITTSBURGH, PENNSYLVANIA.

COMBINED TELEPHONE AND WIRELESS RECEIVER.

Application filed March 10, 1923. Serial No. 624,122.

This invention relates to wireless telephone apparatuses and more in particular to wireless receivers combined with telephone receivers.

5 One of the main objects of this invention is to provide a telephone receiver of great sensitiveness. Another object is to combine with a telephone receiver a wireless receiver; both apparatuses being mounted within the 10 same casing. Still another object of this invention is to provide a wireless telephone set which is compact, simple, and which can be manufactured at low cost. Further features and advantages of this invention will 15 appear from the following description and drawings forming a part of this application.

In the drawings:

Fig. 1 is an enlarged top plan view, partly shown in section, of the combined telephone 20 receiver and wireless receiver.

Fig. 2 is a cross-sectional elevation taken substantially on line 2—2, Fig. 1.

Fig. 3 is an enlarged perspective view showing the method of operation and preferred construction of the sliding contact for the tuning coil.

Fig. 4 is an enlarged view showing the preferred construction of the crystal detector used in this apparatus.

30 Fig. 5 is a top-plan view of the permanent magnet yoke of the telephone receiver.

Fig. 6 is a side-view of Fig. 5.

Reference being had to the various figures, the telephone receiver is composed of a 35 casing 1 threaded at its upper end to receive a cap 2 by means of which the diaphragm 3 is secured. Fastened to the bottom 4 of the casing, by means of a screw 5, is the permanent magnet yoke 6 having substantially the shape of a W with the outer arms 7 and 8 turned inwardly and parallel to the center arm 9. Upon these arms are mounted the pole pieces 10 which are held thereon by means of the depending lugs 11 inserted and 40 riveted in suitable apertures 12 provided in the arms. Each pole piece is magnetized by an individual solenoid 13 of usual construction; said solenoids are properly connected in series to create in the three pole 45 pieces the desired polarity.

The wireless receiving outfit is made up of the tuning coil 14 wound upon a sleeve 15 of suitable insulating material and secured to the magnet yoke by means of the screws 50 16, the heads of which engage interior lugs 17 provided at the lower end of said sleeve.

The tuning of the apparatus is effected by means of the sliding contact feather 18 hingedly mounted on a pin 19 inserted in an insulating ring 20 positioned within the 60 casing 1. The sliding contact is operated by the agency of the threaded thumb-screw 21 mounted in the bottom 4 of the casing and electrically insulated therefrom by means of the bushing 22 and the washer 23. 65 Secured to the sliding-contact is a spring feather 24 having at its outwardly flaring end a small wedge shaped blade 25 which engages the thread of the thumb-screw 21.

By turning the latter in either direction, 70 the sliding contact will be moved over the tuning coil until the correct position has been found. Disengagement of the sliding contact from the tuning coil is prevented by the beads 26 and 27 provided at both ends 75 of the sleeve. It will be noted that when the contact reaches either one of its extreme positions, it will bear against the corresponding bead, and the wedge-shaped blade 25 will simply snap out of the threads as long 80 as the thumb-screw is rotated. The click sound thereby produced by the blade will 85 indicate to the operator that the sliding contact has reached its extreme position and that further rotation of the thumb-screw in that sense is of no avail.

The novel construction of the crystal detector is illustrated in Figs. 1 and 4, and consists of a suitable crystal 28 set in a cup 29 which is slidably mounted in a sleeve 30 90 within which is a coil spring 31 pressing 95 against the cup. The rear end of the sleeve is closed and is provided with a lug 32 having an elongated aperture 33 through which a holding screw 34 is inserted to be 95 screwed into the insulating ring 20. The so-called cat-whisker generally used in connection with crystal detectors is replaced in this construction by a serrated contact-wheel 35 which is obliquely mounted upon a shaft 100 36 and held thereon between the suitably shaped bushings 37. Said shaft is partly guided in a groove 38 cut transversely in the insulating ring 20 and by the bifurcated bearing spring plate 39 secured to the ring 105 by a screw 40. The outer end of the shaft passes through the bottom of the casing 1 and is insulated therefrom in a similar manner as already described for the thumb-screw 21. A knob or disc 41 is secured at 110 the outer end of the shaft to facilitate its operation.

It will be readily understood that, when the contact-wheel is rotated and owing to its inclined position on the shaft, the entire width of the crystal is gradually engaged 5 while at the same time the crystal and cup is given a rotary motion within the sleeve, thereby giving an unlimited number of contact points on the crystal; the contact wheel being held in the chosen position by the 10 spring-plate 39.

The pressure of the crystal upon the contact-wheel is adjusted by pushing the sleeve 30 in either direction; the elongated aperture 33 being made long enough to satisfy 15 the required adjustments.

In Fig. 1 are indicated also the various permanent wiring connections which are provided within the apparatus. The antenna is connected by means of a plug contact 42 to the terminal "A" which in turn is connected to one end of the tuning-coil, and to the phone terminal "P¹" by means of a wire connection 43. The pole solenoids are connected to the terminals P¹ and P², whereas the sliding contact is connected to the ground terminal "G" by the latch-shaped connector 44, best illustrated in Fig. 3. The connections of the crystal detector with the sliding contact and pole terminal P² is effected by means of the wires 45 and 46 respectively which are preferably embedded in a groove 47 cut in the outer circumference of the insulating ring 20.

Although my invention may be used by the public in general, it is especially intended for policemen, taxi-cab drivers and other persons who are subject to orders issued from a central office. Assuming that the apparatus be used by a policeman, he will connect the terminal "A" to an aerial, which is preferably carried as a coil in his cap, and the terminal "G" to a fire-plug or other metallic conductor which insures a good ground connection. If desired, he may connect a second telephone receiver of the ordinary type to the terminals P¹ and P² in order to receive the messages through both ears.

Messages will only be transmitted to the

policeman at predetermined times of the day, so that in the intermediate hours he 50 shall be able to store the instrument away in his pocket while attending to his duties.

The operation of wireless receivers operating with crystal detectors is too well known to those versed in the art as to require further explanation. Suffice it to say that with crystal detectors now commonly used, excellent results have been obtained with this apparatus at distances as great as 30 miles from the sending station. 60

While I have illustrated and described herein the preferred embodiment of my invention, and one which I have found by actual use to be very practical, it may be thought desirable after continued experience 65 to make slight changes in the construction and arrangement of the details of my invention, and I intend to include in this application all such variations as fall within the scope of the appended claims. 70

What I claim is:

1. As an article of manufacture, the combination of a telephone receiver; a wireless receiving apparatus positioned within said telephone receiver and surrounding the poles thereof; said wireless receiver comprising a sleeve member and a tuning coil; a sliding contact mounted for arcuate movement upon said tuning coil; flanges positioned at each end of said sleeve member and adapted to limit the arcuate movement of said contact; screw operated means for moving said contact, and yielding means positioned on said contact adapted to engage the threads of said screw and to snap over said threads 85 when subjected to excessive pressure. 75

2. In a crystal detector for wireless apparatuses, a crystal; a resilient and rotatable support therefor; a serrated contact disc for said crystal and means to rotate said disc; 90 said disc being obliquely disposed to said crystal and adapted to gradually sweep over the whole width thereof and to simultaneously rotate said crystal.

In testimony whereof I affix my signature.

CHARLES H. ALLEN.
